UNITED STATES PATENT OFFICE.

SALOMON DAVIDSON, OF NEW YORK, N. Y.

DESIGN FOR AN ORNAMENTAL CHAIN.

SPECIFICATION forming part of Design No. 13,177, dated August 15, 1882.

Application filed July 13, 1882. Term of patent 7 years.

To all whom it may concern:

Be it known that I, SALOMON DAVIDSON, a citizen of the United States, residing at New York, in the county and State of New York, have invented and produced a new and original Design for Ornamental Chains, of which the following is a specification.

The peculiar feature of this design consists in a string of beads which is interlaced with curb-links, thereby imparting to the chain a novel and characteristic appearance.

In the accompanying drawings, Figure 1 shows a chain having a single string of beads, and Fig. 2 a chain having a double string of beads.

Similar letters indicate corresponding parts.

The letter A designates the chain-links, and B the string of beads, the links being what are commonly known as "curb-links"—namely, plain links of oval or analogous shape—and the string of beads being interlaced therewith.

The string of beads extends the entire length of the chain, and may be used either singly or doubly, as fancy may dictate. When said string is doubled one part may be arranged to intersect the other in its passage through the links, or both may extend in the same direction.

What I claim as new, and desire to secure by Letters Patent, is—

The design for an ornamental chain, consisting of the curb-links and the string of beads interlaced with said links, as shown and described.

In testimony whereof I have hereunto set my hand and seal in the presence of two subscribing witnesses.

SALOMON DAVIDSON. [L. S.]
